[57] CLAIM

The ornamental design for a wood stove, substantially as shown and described.

DESCRIPTION

FIG. 1 is a perspective view of a wood stove showing my new design;

FIG. 2 is a front elevational view thereof;

FIG. 3 is a top plan view thereof shown on a slightly smaller scale;

FIG. 4 is a side elevational view taken from the right side of FIG. 2, and

FIG. 5 is a rear elevational view thereof.
